CLAIM

The ornamental design for a cartridge, as shown and described.

DESCRIPTION

FIG. 1 is a front, top right perspective view of a cartridge illustrating our new design;

FIG. 2 is a front elevational view of the design of FIG. 1; FIG. 3 is a rear elevational view of the design of FIG. 1; FIG. 4 is a left side elevational view of the design of FIG. 1;

FIG. 5 is a right side elevational view of the design of FIG. 1;

FIG. 6 is a top plan view of the design of FIG. 1;

FIG. 7 is a bottom plan view of the design of FIG. 1; and, FIG. 8 is a back, top left perspective view of the design of FIG. 1.

The broken lines shown in the drawings illustrate portions of the cartridge that form no part of the claimed design.

1 Claim, 8 Drawing Sheets
